STOKER

Herman E. Winkler and Carl J. Winkler, Lebanon,
Ind., assignors to U. S. Machine Corporation,
Lebanon, Ind., a corporation of Indiana

Application March 17, 1938, Serial No. 196,321

3 Claims. (Cl. 116—45)

In a common form of small stoker, coal is fed horizontally by means of a feed screw through a pipe communicating with the bottom of a burner placed within the furnace. Pressure generated by the action of the feed screw lifts the fuel within the burner; and to facilitate this lifting action, the burner and feed pipe are joined through a smoothly curved elbow. This construction, for reasons which will become apparent hereinafter, possessed the disadvantages that the coal is not of even depth at all points of the burner and that the coal tends to become segregated with reference to particle size. Such conditions materially interfere with proper combustion.

An additional disadvantage of such stokers arises from the fact that most coals have the property of becoming more or less plastic and adhesive in character as combustion temperature is approached, with the result that masses of coke are formed. These masses may be so dense that the air-supply can not penetrate them to an extent sufficient to consume them as rapidly as they form, and the mass grows vertically, as more fuel is fed into the burner, to form a "coke tree" which frequently rises to a considerable height. These coke trees, both while erect and after they have fallen, tend to produce uneven and inefficient combustion and to prevent the fire from reacting promptly to the heating demand on the stoker.

It is the object of our invention to maintain the upper surface of the fuel bed within the burner free from any pronounced depressions, to avoid segregation of large and small coal particles, and to prevent the formation of coke trees of any considerable height. Further objects of our invention are to facilitate quick response of stoker-fed fires to heating demands, to improve the combustion rate, and to obtain greater efficiency from the fire.

In carrying out our invention, we mount in the burner a rotatable element which acts on the coal within the burner and which, conveniently, is driven from the main feed screw. This rotatable element, in its preferred form, is adapted to prevent segregation and the accumulation of coal near the rear of the burner and also to prevent the formation of coke trees. For the former purpose, it may be provided with a helical flight adapted to move forwardly of the burner coal adjacent the rear wall thereof; and for the latter purpose, the rotatable element may be provided with a laterally projecting finger which, in its rotation, will traverse the zone occupied by coal in the plastic state and break up any incipient

coke formation which might otherwise rise to a considerable height.

The accompanying drawing illustrates our invention: Fig. 1 is a fragmental side elevation of a furnace with an associated stoker; Fig. 2 is a vertical section through the burner of our improved stoker; and Fig. 3 is a view similar to Fig. 2 but illustrating a somewhat modified form of construction.

In the arrangement illustrated in Fig. 1 the stoker is shown in association with a furnace 7 having a fire-pot 8 including a bottom wall 9. The stoker includes a coal bin 10 which, at its bottom, communicates with a feed pipe 11. A feed-screw 12 located within the pipe 11 and extending rearwardly into the bottom of the bin 10 operates, when rotated, to feed coal from the bin 10 through the pipe 11.

At its inner end, the feed pipe 11 communicates with an elbow-shaped passage 13 in a burner-base 14. A burner-head 15 is supported on the base 14 with its interior communicating with the upper end of the passage 13 and with its top extending into a central opening in the bottom wall 9 of the fire-pot. The burner-wall is provided with tuyere sections 16 forming discharge openings for an annular passage 17 surrounding the burner, such passage being supplied with air from a blower 18.

The structure, as so far described, is fairly common. The feed screw 11, blower 18, and feed-screw drive mechanism are driven, as by an electric motor (not shown) which, in most instances, is under automatic control so that the supply of air and fuel to the furnace is proportioned in accordance with the heating requirements. Because of the action of the feed-screw, both in feeding coal into the passage 13 and in causing a measure of recirculation of coal, the finer coal particles tend to accumulate along the outer or rear wall of the passage 13 and to rise in the burner to a greater height than the coarser particles at the front of the burner, and uneven combustion therefore results.

To prevent this unevenness of fuel-distribution, both in respect to depth and particle size, we mount in the burner-base 14 a rotatable element 25 which extends into the coal-containing space within the passage 13 and within the burner. Desirably, but not necessarily, the element 25 is mounted in the rear wall of the passage 13 and projects forwardly toward the center of the burner. As shown in Fig. 2, the rotatable element 25 is mounted in an inclined position, extending forwardly and upwardly into the

burner, but this inclined position is not necessary; and in Fig. 3 we have illustrated the corresponding element 25' as being horizontal.

The rotatable element, whether inclined or horizontal, is conveniently, but not necessarily, driven from the feed screw 12. To this end, there may be mounted in the wall of the passage 13 and in alignment with the feed screw 12 a short shaft 26, the front end of which is coupled to the rear end of the feed screw 12 as by a sleeve coupling 27. The rotatable element 25 or 25' and the shaft 26 are provided with mating gears so that the rotatable element may be driven by the feed screw. In the arrangement illustrated in Fig. 2 bevel gears 28 are employed for this purpose; whereas in the arrangement illustrated in Fig. 3, where the feed screw and rotatable element are parallel, the gears 28' are simple spur gears.

To prevent the segregation of coal sizes in the passage 13 and at the rear of such passage, and thus to prevent the surface of the fuel bed from being higher at the rear of the burner than at the front, the rotatable element 25 or 25' may be provided with a helical flight 30 which, if the feed screw and rotatable element rotate in opposite directions, is of the same hand as the feed screw 12. As the feed-screw 12 tends to force the coal toward the rear of the passage 13 the flight 30, rotating in the opposite direction, tends to move at least a part of such coal forwardly and to counteract the tendency toward segregation of coal sizes and to avoid any effect of the feed screw 12 in packing coal against the rear wall of the burner.

With the structure such as is illustrated either in Fig. 2 or in Fig. 3 it is possible to maintain the upper surface of the fuel bed within the burner 15 at a substantially constant elevation throughout its periphery and to obtain uniform distribution of coal sizes, thus creating better combustion at all points.

To prevent the formation of large coke-masses which would "grow" into coke trees, the rotating element 25 is shown in Fig. 2 as provided at its inner end with a laterally extending finger 31. This finger is so disposed as to traverse that zone in the burner where coal in the more or less plastic state is located, and may be a continuation of the helical flight 30, if the rotatable element 25 embodies such a helical flight. The

zone in which the coal tends to assume the plastic state is located at and a short distance above the lowermost of the tuyères.

As coal is fed to the burner and as the rotatable element 25 rotates, the finger 31 will serve to disturb the more or less plastic coal and thereby to create fissures in the resultant coke formation. Because of such fissures, the coke mass does not "grow" to any great height above the burner, but instead breaks up into relatively small pieces which spread loosely and evenly over the top of the fuel bed in the burner and over the bottom 9 of the fire-pot, as is ideal for efficient combustion.

We claim as our invention:

1. In a stoker having a generally horizontal feed pipe communicating with the bottom of an upwardly opening burner and containing a rotatable feed screw, said burner having tuyères in its side walls, an auxiliary screw rotatably mounted in the rear wall of said burner below said tuyères on an axis generally perpendicular to such rear burner-wall, and gearing interconnecting said two screws, said auxiliary screw projecting forwardly toward the center of the burner and being of such a hand as to produce within the burner continuous movement of fuel from the vicinity of the rear burner-wall toward the center of the burner.

2. In a stoker having a generally horizontal feed pipe communicating with the bottom of an upwardly opening burner having tuyères in its side walls, mechanism for feeding fuel through said feed-pipe into said burner, a screw rotatably mounted in the rear wall of the burner below said tuyères on an axis generally perpendicular to such rear burner-wall, said screw projecting from the rear burner-wall forwardly toward the center of the burner, and means for rotating said screw to move fuel continuously toward the center of the burner from the vicinity of the rear wall thereof.

3. The invention set forth in claim 2 with the addition that said screw is provided near the center of the burner with a laterally projecting fuel-agitating finger which, in its rotation, passes through a zone extending above and below the lowermost of said tuyères.
